MEAT-SLITTING MACHINE

Joseph P. Spang, Quincy, Mass., assignor to Cube
Steak Machine Company, Inc., Boston, Mass.,
a corporation of Massachusetts

Application August 25, 1937, Serial No. 160,840

12 Claims. (Cl. 17—26)

This invention relates to a meat-slitting machine and it has for its general object to provide a novel machine of this type embodying rotary slitting knives and in which the meat to be slit is carried by a meat-supporting plate which is mounted to be reciprocated beneath the knives at a speed independent from the rotary speed of the knives, the construction being such that during the forward movement of the plate 10 the knives act on the meat to slit the latter and during the return movement of the plate the slice of meat is discharged therefrom.

Since the reciprocating movement of the meat-supporting plate is independent of the speed of rotation of the knives, it is possible to move the plate beneath the knives during the slitting operation at a speed which is best adapted to perform the meat-slitting operation.

While any suitable means may be employed 20 for giving the meat-supporting plate its reciprocating movement, I have herein shown a construction where the plate is adapted to be manually operated.

In the drawings:
25 Fig. 1 is a side view of a meat-slitting machine embodying the invention;

Fig. 2 is a section through the frame on the line 2—2, Fig. 1, the motor, the driving connection between the motor and the knife shafts and 30 various parts such as 43, 44, 45, 47, 49, 53, being shown in elevation;

Fig. 3 is a section on the line 3—3, Fig. 2;
Fig. 4 is a fragmentary view on substantially 35 the line 4—4, Fig. 2 but showing the sprocket wheels and sprocket chains in elevation;

Figs. 5, 6 and 7 are fragmentary sectional views illustrating different ways in which the machine may be used;

Fig. 8 is a perspective view of the meat-supporting member;

Fig. 9 is a fragmentary view illustrating the manner in which the meat-supporting member is pivotally mounted;

Figs. 10, 11 and 12 illustrate different ways in 45 which a slice of meat may be slit by means of the construction shown;

Figs. 13 and 14 show a reversible meat-supporting plate for use in the slitting machine herein illustrated, which plate presents a smooth face 50 on one side and a rough face on the other.

My improved meat-slitting machine comprises a suitable frame 1 in which is journaled one or more knife shafts carrying rotary slitting knives. In the particular embodiment of the invention illustrated there are two such knife shafts 2 and

3, the knife shaft 2 carrying an upper set of rotary knives 4 for making slits in the top side of a slice 8 of meat and the other knife shaft 3 carrying a series of rotary knives 5 for cutting slits in the under side of a slice of meat. These 5 shafts 2 and 3 are journaled in suitable bearings carried by the end members 6 and 7 of the frame 1. The invention would not be departed from, however, if the machine were made with a single knife shaft and a single set of rotary knives.

In accordance with this invention the slice of meat 8 to be slit is carried by a meat-supporting member 9 which is adapted to be reciprocated in guides or ways 10 carried by the frame, the 15 construction being such that during the movement of the member 9 in one direction the slice 8 of meat will be carried past the knives and will be slit thereby, while during the return movement of said member the slit slice of meat 20 will be discharged therefrom.

Where an upper and a lower set of knives is employed as herein illustrated, the meat-supporting plate 9 will be preferably provided with slots 11 registering with the knives and in which the 25 knives of the lower set may operate during the reciprocating movement of said plate 9.

The reciprocating movement of the meat-supporting plate 9, which movement is independent of the speed of rotation of the knives, 30 may be imparted thereto by any suitable means. For illustrative purposes I have herein shown the plate 9 as provided at one end with a handle 12 by which it may be moved manually back and forth in the ways 10.

In using the device, the meat-supporting plate 9 will be moved backwardly in the ways 10 into the position shown in Fig. 1 and a slice 8 of meat will then be placed on the member 9. The operator then pushes the member 9 forwardly in the ways 10 into the dot and dash line position, 40 Fig. 1, thereby carrying the meat into position to be acted upon by the slitting knives.

This forward movement of the plate 9 is sufficient to carry the meat entirely past the slitting knives, during which movement the knives cut slits in the meat, and on the return movement of the plate back to its initial position shown in Fig. 1 the slit slice of meat will be discharged therefrom.

The ways 10 in which the meat-supporting plate 9 is guided comprises two channel members embracing the edges of the plate, which channel members are connected together by cross bars 59. The channel members 10 are not con- 55

nected beyond each cross bar so that the space between the channel members at the right hand end in Fig. 1 is free for the movement of the operator's hand in manipulating the plate 9, and the space between said members 10 at the left hand end is also open and unobstructed for the discharge of the slit slice upon the return movement of the plate 9.

The movement of the slice 8 of meat past the knives will cut slits in the meat extending in the direction of feed. If it is desired to cut a second series of slits in the meat extending across the slits cut by the first pass of the meat beneath the knives, then the slice of meat will be fed a second time past the knives.

13 indicate resilient stripper or hold-down fingers which are associated with the knives 4 and which serve to retain the meat on the sliding meat-supporting plate member 9 during the slitting operation and which also prevent the meat from being lifted off from the plate by the rotative movement of the knives. These stripper fingers may have any suitable or usual construction and are herein illustrated as similar to those shown in my co-pending application, Serial No. 91,676, filed July 21, 1936, which issued as Patent No. 2,216,216 on October 1, 1940. The stripper fingers 13 are carried by a head member 14 which is removably mounted on a supporting bar 15, the latter being carried by arms 16 rigid with the ways 10.

As stated above, the slitting of the meat is accomplished by the operator moving the meat-supporting member 9 forwardly a sufficient distance to carry the slice 8 of meat past the knives. When this has been done the operator returns the member 9 to its initial position and during the return movement the stripper fingers 13 serve to push the slice of meat off from the left hand end 40 of the returning member 9. The frame 1 is provided with a delivery chute 17 onto which the slice of meat is discharged from the member 9, and this chute delivers the slice of meat into the pan or receptacle 18 which is shown as mounted on a suitable bracket 19. The feeding of the slice 8 of meat past the knives causes slits to be cut in the meat extending in the direction of feed and, as stated above, if it is desired to cut a second series of slits in the meat crossing the slits of the first series then the operator will take the slice of meat from the pan or receptacle 18 and place it again on the meat-supporting plate 9 when the latter is in retracted position and with the slits in the meat extending transversely to the direction of feed, and he will then a second time move the plate 9 forwardly to carry the meat past the knives. During the return movement of the plate 9 the doubly slit slice of meat will be discharged from said plate into the receptacle 18 as above described.

The knives may be rotated by any suitable means. I have, however, herein shown them as being driven from an electric motor, and I preferably employ a driving connection between the motor and the knives by which both the upper and lower knives will be rotated in the same direction and the upper knives 4 will be rotated in such a direction that the frictional engagement of the knives with the meat tends to pull the meat forwardly.

In other words, the driving mechanism I prefer to use is such that both the upper knives 4 and the lower knives 5 will be rotated clockwise in Figs. 1 and 3.

75 The motor for operating the knives is indicated

at 20 and it is mounted on a platform 21 that is pivotally connected at one edge to the frame 1 as indicated at 22. The motor shaft carries a pulley 23 which is connected by a driving belt 24 to a pulley 25 on the upper knife shaft 2 so that said 5 knife shaft is driven from the motor.

The lower knife shaft 3 is driven from the upper knife shaft 2 and for this purpose the knife shaft 2 has thereon a sprocket wheel 26 which is connected by a sprocket chain 27 to a sprocket wheel 10 28 fast on the knife shaft 3. This sprocket chain 27 runs over a tension member 29 by which the sprocket chain is kept taut. This tension member is in the form of a sprocket wheel journaled in a carrier 30 which is provided with a stem 31 15 extending through a portion 32 of the frame 1. 33 is a coiled spring encircling said stem and confined between the portion 32 of the frame and a collar 34 on the stem 31. The spring 33 tends to hold the sprocket chain 27 under proper tension.

The guiding member 10 for the meat-supporting plate 9 is capable of vertical adjustment thereby to vary the relative depths of the slits cut in the top and bottom faces of the slice 8. 25 This member can be so adjusted that the lower knives 5 will be entirely below the slice 8 so that slits will be cut in the upper face only of the meat. Or said guiding member 10 may be adjusted into a vertical position in which the lower knives 5 as 30 well as the upper knives 4 will cut slits in the meat, and by varying the adjustment of the member 10 vertically the relative depths of the slits cut in the top and bottom faces of the meat can be varied as desired. This adjustment of the 35 member 10 is provided for by pivotally connecting the two ways 10 to the frame and providing means for swinging the ways vertically about their pivot axis. As herein shown each of the ways 10 is formed with a trunnion 35 which is journaled in 40 suitable bearing 36 in the frame. For vertically adjusting the member 10 the latter is connected by a link 37 to an arm 38 fast on a rock shaft 39 that is journaled in the frame, and said rock shaft also has fast thereto another arm 40 which 45 constitutes a handle by which the rock shaft can be turned thereby swinging the left hand end of the guiding member 10 up or down as shown by the dotted lines in Fig. 1. The handle 40 is provided with a spring-pressed locking pin 41 adapted to engage in any one of a plurality of holes 42 formed in the frame 1 thereby to hold the guiding member 10 in its adjusted position.

I have also provided means for adjusting the two knife shafts 2 and 3 toward and from each other.

For this purpose each shaft is journaled at each end in an eccentrically-mounted bearing 43 which in turn is mounted for turning movement in the end member of the frame. The two eccentric bearings 43 for the upper shaft 2 are connected together by a yoke 44 and these eccentrics can be turned for adjusting the upper shaft up or down through the medium of a handle 45. This handle is shown as journaled in the cover 65 plate 46 and it is connected to the eccentric 43 through a yoke 47.

A similar construction is employed for adjusting the eccentric bearings 43 for the lower shaft 3 said bearings being connected by the yoke member 48 and one of the bearings being connected by another yoke member 49 to an arm 50 which is journaled in the cover plate 46. Each of the arms 45 and 50 carry at its end a spring-pressed locking pin 51 adapted to engage any one of a 75

plurality of apertures 52 formed in the cover plate 46. Each locking pin is provided with a head 53 by which it may be withdrawn from the locking aperture against the action of the spring 54. If it is desired to slit the slices 8 of meat so that the slits will be entirely on the upper face thereof and so that the lower face will present a thin film 62 of unslit meat, which is the usual method of making what is known as "cube steak," then the guiding member 10 will be adjusted into the position shown in Fig. 3, in which position the upper knives 4 will cut nearly through the slice 8 of meat but the lower knives 5 will just clear the meat.

If it is desired to slit the meat on both the top and bottom faces and to leave a thin film 55 of unslit meat in the center of the slice, then the guiding member 10 will be lowered into the position shown in Fig. 7 and when the slice 8 of meat is carried through the machine with this adjustment there will be slits 53 cut in the upper face of the meat by the knives 4 and slits 54 cut in the lower face of the meat by the knives 5, and there will also be a thin film 55 of meat between the upper and lower slits. If it is desired to cut clear through the meat so as to cut a slice of meat into strips then the guiding member 10 will be adjusted upwardly into the position shown in Fig. 5 so that the upper edge of the knives 4 will operate in the slits 11 of the meat-supporting plate 9. With this adjustment the upper knives 4 will cut clear through the slices of meat thus cutting it into strips.

So-called "Swiss steak" is made by cutting shallow slits in both top and bottom faces of the meat as shown in Fig. 12. When it is desired to slit meat in this way the eccentric bearings 43 of the knives are adjusted to separate the upper and lower knives from each other as shown in Fig. 6 and then the member 10 may be adjusted vertically into a position wherein shallow slits 56 will be cut in both faces of the slice of meat by both sets of knives.

Inasmuch as the stripper fingers 13 are carried by the ways 10 said fingers will move with the ways when the latter are adjusted vertically and, therefore, said fingers will have the same action on the slice of meat regardless of any vertical adjustment of the guiding member 10.

In the construction herein illustrated the driving means for the knives 4 and 5 is such as to cause the upper knives 4 to rotate considerably faster than the lower knives 5. Fig. 4 shows the sprocket wheel 26 on the upper knife shaft 2 as considerably smaller than the sprocket wheel 28 on the lower knife shaft 3, and this construction will cause the lower knife shaft 3 to rotate at a slower speed than the upper knife shaft 2.

The upper knives are also shown as slightly larger in diameter than the lower knives 5 although this is not essential to the invention. However, if the upper knives are larger this fact will increase the surface speed of the knives 4 relative to those of the knives 5.

As the meat is fed between the knives the friction of the rapidly rotating upper knives 4 on the meat will tend to pull the meat forward and this will assist in feeding the meat-supporting plate forward. When the guides 10 are adjusted so that the meat is being slit on the top face only, the friction of the knives 4 on the meat may be sufficient to feed both the plate 9 and the meat forward so that the operator has little to do except to control the feeding movement of the plate.

When the parts are adjusted as shown in Fig. 3 the lower knives 5 occupy the slits 11 in the plate 9, and during this return movement the friction of the knives against the sides of the slits 11 or against any meat fragments which may be retained on the plate will help to give the plate its return movement.

While I have herein illustrated a meat-slitting machine having two sets of knives, one for cutting slits in the upper face of the meat and the other for cutting slits in the lower face of the meat, yet if it is desired to cut slits on the upper face only of the meat the presence of the lower set of knives 5 will not be essential and, therefore, said knives could be omitted without departing from the invention.

In Figs. 13 and 14 I have shown a reversible meat-supporting plate which is designated 9-a. This meat-supporting plate is provided with the slots 11 similar to the meat-supporting plate 9 and is also provided with a handle 12-a by which it may be moved back and forth in the ways 10. The plate is reversible so that it can be placed in the ways either side up. One face of the plate is provided with transverse corrugations 70 and the other face is free of such corrugations. For slitting some kinds of meat best results are secured if the meat is supported on a meat-supporting plate having a roughened surface while for slitting other kinds of meat best results can be secured if the meat is supported on a smooth surface. The reversible plate shown in Figs. 13 and 14 provides a construction which allows the operator to support his meat on either a roughened surface or a smooth surface.

61 indicates a stop which is pivotally secured to the end of one of the ways 10 and which limits the backward movement of the plate 9. When the plate is to be withdrawn from the ways this stop 61 may be swung to one side about its pivot.

I claim:

1. A meat-slitting machine comprising a set of upper rotary slitting knives, a set of lower rotary slitting knives, means to rotate the knives of both sets, a guiding member having ways extending from one to the other side of said sets of knives, a meat-supporting plate supported by said ways and free to be moved therein continuously in a forward direction and continuously in a backward direction independent of the rotary movement of the knives, the forward movement being sufficient to carry a slice of meat supported on the plate from one side of the knives, between the knives of the two sets and to the other side of said knives, said plate having slots in which the knives of one set operate, whereby said knives will cut in both sides of the meat continuous slits extending across said slice in the direction of feed, said plate having means for manually giving it both its forward and backward continuous movement in said ways at a speed less than the peripheral speed of the knives whereby the knives will slit meat with a draw cut.

2. A meat-slitting machine comprising a set of rotary slitting knives, means to rotate the knives, a vertically adjustable guiding member beneath the knives, said guiding member having ways, a manually operable meat-supporting plate having at all times a free back-and-forth sliding movement of limited extent in said ways independently of the rotative movement of the knives and adapted to carry a slice of meat past the knives and then to be returned manually to its initial position from any point in its forward move-

ment, and means for adjusting the guiding member.

3. A meat-slitting machine comprising a set of rotary slitting knives, means to rotate said knives, a vertically adjustable guiding member beneath the knives, said guiding member having ways, a manually operable meat-supporting plate having at all times a free reciprocatory movement of limited extent in said ways which is independent 10 of the rotary motion of the knives, said plate being adapted during its forward movement to carry a slice of meat thereon past the knives, means to discharge the slit slice of meat from the plate during its return movement, and means for adjusting 15 the guiding member vertically.

4. A meat-slitting machine comprising a set of upper slitting knives, a set of lower slitting knives, means to rotate both sets of knives, a guiding member having ways, a manually operable meat-supporting plate freely slideable forwardly and backwardly in said ways independently of the rotative movement of the knives and capable of an amplitude of movement sufficient to carry a slice 20 of meat from one to the other side of the knives 25 and between the two sets of knives, said plate having slots in which the knives of one or both sets may operate.

5. A meat-slitting machine comprising two sets 30 of rotary slitting knives, one above the other, means to rotate said knives, a guiding member having ways, a manually operable meat-supporting plate having a free forward and backward sliding movement in said ways, which movement is independent of the rotative movement of the 35 knives, said plate being adapted during its forward movement to carry a slice of meat thereon between the two sets of knives, and means to discharge the slit slice of meat from the plate during its return movement.

40 6. A meat-slitting machine comprising two sets of rotary slitting knives, one above the other, means to rotate said knives, a guiding member having ways, a manually operable meat-supporting plate having a free reciprocatory sliding 45 movement in said ways, which movement is independent of the rotative movement of the knives, said plate being adapted during its forward movement to carry a slice of meat thereon between the two sets of knives, means to discharge the slit slice of meat from the plate during 50 its return movement, and means to adjust the guiding member vertically thereby to vary the relative depth of the slits cut in the top and bottom faces of the meat.

55 7. A meat-slitting machine comprising a set of rotary slitting knives, means to rotate the knives, a guiding member beneath the knives, a manually operable meat-supporting plate free at all times to be reciprocated manually in said 60 guiding member independent of the rotary motion of the knives, said plate being adapted during its forward movement to carry a slice of meat past the knives, and stripper means acting on the meat while it is being slit to hold it on the plate, said stripper means also acting to discharge the slit slice of meat from the plate upon its return 65 movement.

8. A meat-slitting machine comprising a set of rotary slitting knives, means to rotate the knives, a vertically adjustable guiding member beneath the knives, said guiding member having ways, a meat-supporting plate freely slideable in said ways independently of the rotative movement of the knives and adapted to carry a slice of meat past the knives, a stripper assembly carried by and adjustable with the guiding member and adapted to hold the meat to said plate during the slitting 10 operation, and means for adjusting the guiding member vertically.

9. A meat-slitting machine comprising a set of rotary slitting knives, means to rotate the knives, a vertically adjustable guiding member 15 beneath the knives, said guiding member having ways, a meat-supporting plate freely slideable in said ways independently of the rotative movement of the knives and adapted to carry a slice of meat past the knives, means for adjusting the 20 guiding member toward and from the knives, a stripper assembly carried by and adjustable with the guiding member and constructed to hold the meat to said plate during the slitting operation and to discharge the meat from the plate during 25 its return movement.

10. A meat-slitting machine comprising a set of upper slitting knives, a set of lower slitting knives, means to rotate the knives of both sets in the same direction, a guiding member having ways, 30 a meat-supporting plate freely slideable in said ways independently of the rotative movement of the knives and adapted to carry a slice of meat between the two sets of knives, said plate having slots in which the knives of one set may operate. 35

11. A meat-slitting machine comprising a set of rotary knives, means to rotate said knives, a guiding member beneath the knives, said guiding member having ways, a manually-operable meat-supporting plate having at all times a free back-and-forth sliding movement in said ways, which movement is independent of the rotative movement of the knives, said meat-supporting plate having a handle at one end by which it may be manually moved forwardly in said ways and then 40 manually returned to initial position, said plate being adapted during its forward manual movement to carry a slice of meat thereon past the knives, and means to discharge the slit slices of meat from the plate during its manual return 45 movement.

12. A meat-slitting machine comprising a set of rotary slitting knives, means to rotate the knives, a guiding member beneath the knives, a manually operable meat-supporting plate free at 55 all times to have a continuous forward and a continuous backward movement in said guiding member of sufficient amplitude to convey a slice of meat on said plate from one side to the other of said knives during the forward movement, said plate having means by which it may be given its manual forward and backward movement and being adapted during its forward movement to carry a slice of meat past the knives, and means to discharge the slit slice of meat from the plate 60 during its return movement.

JOSEPH P. SPANG.
